GREASE CONTAINER FOR USE IN GREASE GUNS

Filed Feb. 9, 1925

Louis G. Hill

By John Harness

Attorney

UNITED STATES PATENT OFFICE.

LOUIS G. HILL, OF MORENCI, MICHIGAN.

GREASE CONTAINER FOR USE IN GREASE GUNS.

Application filed February 9, 1925. Serial No. 7,785.

It is the primary object of my invention to provide a grease container of simple and inexpensive construction that can be easily and quickly placed into or removed from a grease gun.

It is another object of my invention to provide a container wherein grease may be shipped or stored and at the same time held for immediate use in a grease gun.

With the above and other objects in view, my invention consists in the arrangement, combination and construction of the various parts of my improved device as described in the specification, claimed in my claim and shown in the accompanying drawing, in which:

Fig. 1 is a front elevation of my improved device showing its position in a grease gun.

Fig. 2 is a front elevation of my improved device ready for shipment.

In the construction of my improved device, I provide a paper or cardboard tube 10, into which the top or wooden block head 11, and the wooden bottom or base 12 are fitted.

On the underside of the head 11 is placed a paper or cardboard cup 13 that has the flanged end 14, and on the inner side of the base 12 is placed a similar cup 15 with the flanged end 16. The flanged ends 14 and 16 fit tight against the inner surface 17 of the container 10, thus preventing the extrusion of grease around the edges of the container when pressure is placed on the head 11. The base 12 with the cup 15, has an aperture 18 therein, which provides the outlet for the grease.

The inner surface 17 of the container 10, the cup 13 and the cup 15 may be paraffined, or otherwise chemically treated, so that the grease will not penetrate through them.

Nails 19 are placed in the head 11 so that their ends 20 extend from the underside thereof.

When my improved device is shipped or placed in storage, a plug 21 with the tapered shank 22 is forced into the aperture 18, and the paper covers 23 are secured over

and around the top and bottom of the container 10 by the brads 24 which extend into the head 11 and the base 12, as shown in Fig. 2.

In the practical use of my device, the plug 21 is removed from the aperture 18, and the block 12 of the container placed on the base 26 of a grease gun 27, so that the tapered nipple 25 on the base extends into the aperture 18 of the grease container with the top of the nipple substantially flush with the top of the block 12. The head 11 is likewise placed under the plunger 29 of the grease gun so that the flanged head 30 thereof extends over the nails 19. Thus when downward pressure is applied on the plunger 29, the same will press the head 11, which in turn forces the grease out through the aperture 18 and the nipple 25 into the outlet 28 of the grease gun 27.

When the grease is almost exhausted, the ends 20 of the nails 19 in the head 11 will be forced into the bottom 12, thereby making it impossible to re-use the container 10.

It will be noted that my device provides an economical and practical construction for the handling and disposition of grease and also one wherein complete removal of the grease in the container is obtained without possibility of leakage.

It is obvious that various changes may be made in the arrangement, combination and construction of the various parts of my improved device without departing from the spirit of my invention, and it is my intention to cover by my claim such changes as may be reasonably included within the scope thereof.

What I claim is:

A grease container consisting of a cardboard or paper tube, a wooden head and a wooden base fitted in said tube and nails extending through said head so that the ends of said nails are adapted to enter the base when the head is forced down.

LOUIS G. HILL.
